UNITED STATES PATENT OFFICE

CHESTER W. LYMAN, OF NEW YORK, N. Y., ASSIGNOR TO INTERNATIONAL PAPER COMPANY, OF NEW YORK, N. Y., A CORPORATION OF NEW YORK.

CORE FOR ROLLS.

No. 805,867.

Specification of Letters Patent.

Patented Nov. 28, 1905.

Application filed January 11, 1905. Serial No. 240,554.

To all whom it may concern:

Be it known that I, CHESTER W. LYMAN, a citizen of the United States, residing at New York, county of New York, and State of New York, have invented certain new and useful Improvements in Cores for Rolls, fully described and represented in the following specification and the accompanying drawings, forming a part of the same.

10 This invention relates to certain improvements in cores for use with web material—such, for instance, as paper, cloth, &c.

15 It is customary in mills to wind web material on tubular cores, the rolls of material being thereafter shipped to the users on the cores, the rolls being mounted by the users on suitable supports, which engage the cores so that the material may be unwound therefrom. Various devices are employed, the purpose of 20 which is to firmly secure the cores to the shafts on which they are mounted to wind the web material on and unwind it from the cores.

25 This invention has for its object to produce an improved device for locking or securing cores of rolls to the supports on which they are mounted either for the purpose of winding material thereon or unwinding it therefrom, which shall be simple, and therefore cheap to construct, and which shall be effective in operation.

30 With this and other objects not specifically referred to in view the invention consists in certain constructions and in certain parts, improvements, and combinations, such as will be 35 hereinafter fully described and then specifically pointed out.

Referring to the drawings, Figure 1 is a sectional side elevation illustrating one form of the improved locking device in connection with 40 a shaft on which the core or shell is supported. Fig. 2 is a section on the line 2 2 of Fig. 1. Fig. 3 is a side elevation of one form of one 45 of the locking members employed; and Figs. 4 and 5 are perspective and sectional views, respectively, of one form of coacting locking member employed.

Referring to the drawings, 1 indicates a shell which may be of any suitable material, though paper will usually be employed as the material 50 on account of its cheapness, lightness, and other advantages. This shell 1 carries a locking device which may be varied widely in its construction and which may be variously located with respect to the shell. In the par-

ticular construction selected to illustrate the 55 invention this locking device embodies a stud having a head 2 and a stem 3, this stem being provided with a recess 4, the purpose of which will be hereinafter explained. When the locking device consists of a stud, it will be firmly 60 secured to the material of the shell in any suitable manner. In the particular construction shown this is accomplished by passing the stem of the stud through the material of the shell, the outer end of the stud being then 65 clenched, as is clearly shown in Figs. 1 and 2, so that the stud is firmly secured to the shell. When the construction employed embodies the invention in its best form, the locking device will be so secured to the shell that the 70 effective locking part will lie in the interior of the shell, thus avoiding any danger of breaking off the locking device or of tearing it loose from or out of the shell in handling. The locking device will be used in connection 75 with a coacting locking member which may be variously constructed; but this member will be provided with a groove or recess with which the effective locking portion of the device on the shell will engage. A convenient and sat- 80 isfactory form of locking member is that illustrated in the drawings, which consists of a bushing 6, having a collar 7 thereon, this bushing being designed to be firmly secured to a shaft, as 8, or to any other supporting 85 member by means of a set-screw 9 or in any other suitable manner. The locking member in its best form may be provided with a plurality of recesses 10, two of said recesses being shown, with either of which the locking 90 member on the shell may engage when the shell is shoved onto its support, according as one or the other of the recesses is in convenient position. The collar 7 forms an abutment against which the ends of the shell may 95 bear.

While the coacting locking member above referred to is shown as a bushing located so as to engage a locking projection located near the end of the core, it may, if desired, as before indicated, be otherwise constructed or be located at other points on the shaft or other support.

It will be seen that the construction described forms a very simple and at the same 105 time a very effective locking device for cores and that it is exceedingly cheap in construction.

While the construction illustrated embodies the invention in its best form, it is to be understood that changes and variations may be made in the construction without departing 5 from the invention.

What is claimed is—

1. In a core for rolls, the combination with a shell, of a locking projection carried by the shell and located wholly within the interior of 10 the shell.
2. In a core for rolls, the combination with a shell, of a stud passed through the material of the shell and firmly secured thereto, the head of the stud forming a locking projection. 15
3. In a core for rolls, the combination with a shell, of a stud passed through the material of the shell and firmly secured thereto, the head of the stud lying in the interior of the shell and forming a locking projection. 20
4. In a core for rolls, the combination with a shell, of a stud passed through the material of the shell and secured thereto by clenching, the head of the stud forming a locking projection. 25
5. The combination with a shell forming a core for rolls, of a locking member extending into the interior of the shell and permanently secured thereto, a shaft, and a recessed locking member coacting with the locking projection. 30
6. The combination with a shell forming a core for rolls, of a stud passed through the material of the shell and firmly secured thereto, the head of the stud forming a locking projection, a shaft, and a recessed locking member coacting with the locking projection. 35
7. The combination with a shell forming a core for rolls, of a stud passed through the material of the shell and firmly secured thereto, the head of the stud forming a locking projection, a shaft, and a recessed locking member secured to the shaft and coacting with the locking projection. 40
8. The combination with a shell forming a core for rolls, of a stud passed through the material of the shell and firmly secured there- 45

to, the head of the stud lying within the shell and forming a locking projection, a shaft, and a recessed locking member secured to the shaft and coacting with the head of the stud. 50

9. The combination with a shell forming a core for rolls, of a stud passed through the material of the shell and firmly secured thereto by clenching, the head of the stud forming a locking projection, a shaft, and a recessed 55 bushing secured to the shaft and coacting with the stud.

10. The combination with a shell forming a core for rolls, of a stud passed through the material of the shell and firmly secured thereto by clenching, the head of the stud lying within the interior of the shell and forming a locking projection, a shaft, and a recessed 60 bushing secured to the shaft and coacting with the stud. 65

11. The combination with a shell forming a core for rolls, of a stud passed through the material of the shell and firmly secured thereto by clenching, the head of the stud forming a locking projection, a shaft, and a bushing 70 secured to the shaft and having a plurality of recesses therein, one of said recesses coacting with the head of the stud to hold the shell in place. 75

12. The combination with a shell forming a core for rolls, of a stud passed through the material of the shell and firmly secured thereto by clenching, the head of the stud lying within the interior of the shell and forming a locking projection, a shaft, and a bushing 80 secured to the shaft and having a plurality of recesses therein, one of said recesses coacting with the head of the stud to hold the shell in place. 85

In testimony whereof I have hereunto set my hand in the presence of two subscribing witnesses.

CHESTER W. LYMAN.
